UNITED STATES PATENT OFFICE.

JOSEPH H. LYNCH, OF ASBURY PARK, NEW JERSEY.

LAUNDRY TAG AND HOLDER.

Application filed June 24, 1925. Serial No. 39,287.

To all whom it may concern:

Be it known that I, JOSEPH H. LYNCH, a citizen of the United States, and a resident of Asbury Park, county of Monmouth, State of New Jersey, have invented certain new and useful Improvements in Laundry Tags and Holders, of which the following is a specification.

In the laundry trade, in the handling of 10 the semifinished articles, it is essential to maintain identification of the individual pieces in batches by means of identification tags.

The present invention relates to certain 15 improvements in the construction of the tags and of holders whereby the pieces of the laundry may be assembled in their respective batches in a convenient manner.

The invention is illustrated in the accompanying drawing, in which

Figure 1 is a perspective view showing a holder with several tags supported thereby.

Figure 2 is a longitudinal section through the center of the holder.

Figure 3 is a transverse section on the line 3—3 Figure 2.

Figure 4 is a transverse section through the holder showing the tag held thereby.

Figure 5 is a similar view with the tag 30 being released.

Figure 6 is a perspective view of the tag in its unclasped position.

The holder consists essentially of an outer tube 1 and an inner tube 2, the latter turning freely within the former and both having slots in their lower portions. The outer tube is supported rigidly by a wall support 3 adapted to be fastened to any vertical surface. This wall support 3 is box-shaped and has functioning within it a rocking lever 4 that is firmly secured to the inner end of the inner tube 2. The rocking lever 4 is held at one end of a slot 5 in the support 3 by means of a spring 6 and when so held, the slots do not register, as shown in Figure 4, whereas when the rocking lever is pressed downward, the slots in the inner and outer tubes 1 and 2 are made to register, as shown in Figure 5. A laundry tag 7 is made of a bent strip of metal 8, the loop end of which is formed in a cylindrical shape as shown at 9, and the size of this cylindrical end is such that when the tag is slipped into the slotted tubes at the ends thereof, the said 55 cylindrical end 9 will not allow the tag to

fall through the slots if the slots are out of register, as shown in Figure 4, but will fall through the slots when they are in register, as shown in Figure 5. The tag is of the general construction shown in my copending application Serial No. 7,551, filed February 7, 1925, and has a sliding portion 10 that serves to lock the two halves 8 together when the tag is clamped onto a piece of goods. I have found that this locking slide will in the laundering processes sometimes become loose and allow the tag to become separated from the goods. This trouble I have found can be obviated by making the tag with a slight protuberance 11, which is small enough to 65 slip under the bifurcated end of the slide shown at 12 and hold the slide in its clamping position with sufficient force to prevent its accidental movement. When, however, sufficient pressure is applied longitudinally 70 to a projecting lug 13 on the slide, the bifurcation 12 may be made to ride over the projection 11 until the parts assume the position shown in Figure 6.

In operation the support is utilized as 80 follows. As the clothes are sorted out in batches, they are assembled on the holders one batch to each holder, that is to say, the tags carrying one identification number will all be assembled on one holder one at a time. 85 They are thus assembled by slipping the tag into the end of the holder so that the enlarged end 9 of the tag will be supported by the inner tube as shown in Figure 4. When it is desired to remove the batch 90 from the holder all that is necessary is to press down the lever 4 with one hand while with the other hand the entire batch is grasped or they can be allowed to drop into a basket or onto the floor. 95

I claim:

1. A tag holder comprising an inner and an outer tube, each tube having a slotted portion, and means for causing one tube to rotate with respect to the other tube to 100 change the registering of the slots.

2. A tag holder comprising an inner and an outer tube, each tube having a slotted portion, means for causing one tube to rotate with respect to the other tube to change 105 the registering of the slots, and means for normally holding the tubes in the position of least registry.

3. A tag holder comprising an inner and an outer tube, each tube having a slotted 110

portion, means for causing one tube to rotate with respect to the other tube to change the registering of the slots, and resilient means for normally holding the tubes in the 5 position of least registry.

4. A tag holder comprising an inner and an outer tube, each tube having a slotted portion, means for causing one tube to rotate with respect to the other tube to change 10 the registering of the slots, resilient means for normally holding the tubes in the position of least registry, and means for increasing the registering of the slots.

5. A tag holder comprising an inner and 15 an outer tube, each tube having a slotted portion, means for causing one tube to rotate with respect to the other tube to change the registering of the slots, resilient means for normally holding the tube in the 20 position of least registry, and a rocking lever

attached to one of the tubes for increasing the registering of the slots.

6. In apparatus for assembling laundry, the combination of identification tags having an enlarged end, a tag holder comprising 25 a tube with a slot in its lower portion narrower than the said expanded end on the tag so as to form a support for the same.

7. In apparatus for assembling laundry, the combination of identification tags having an enlarged end, a tag holder comprising 30 an inner and an outer tube both slotted at the lower portion and adapted to form an opening narrower than the extended end of the tag when in one position and to allow 35 the opening to be increased so as to permit the enlarged end of the tag to pass freely through the slots in the tube when in another position.

JOSEPH H. LYNCH.
